US0D1054880S

(12) **United States Design Patent** (10) Patent No.: **US D1,054,880 S**
(45) Date of Patent: **** Dec. 24, 2024**

(54) **PACKAGING FOR FOOD**

(71) Applicant: **COMPAGNIE GERVAIS DANONE**,
Paris (FR)

(72) Inventor: **Chema Sanchez**, Barcelona (ES)

(**) Term: **15 Years**

(21) Appl. No.: **35/518,984**

(22) Filed: **Jul. 27, 2023**

(80) **Hague Agreement Data**

Int. Filing Date: **Jul. 27, 2023**

Int. Reg. No.: **DM/232877**

Int. Reg. Date: **Jul. 27, 2023**

Int. Reg. Pub. Date: **Nov. 10, 2023**

(51) **LOC (14) Cl.** 09-03

(52) **U.S. Cl.**

USPC **D9/756**

(58) **Field of Classification Search**

USPC D9/737, 756, 761, 414, 428, 430-433

CPC B65D 1/30; B65D 1/10; B65D 85/72

See application file for complete search history.
